L. HOLLOWELL

Des. 156,509

AMUSEMENT BAR

Filed Oct. 7, 1947

UNITED STATES PATENT OFFICE

156,509

AMUSEMENT BAR

Lafayette Hollowell, Detroit, Mich.

Application October 7, 1947, Serial No. 141,779

Term of patent 14 years

(Cl. D33—13)

To all whom it may concern:

Be it known that I, Lafayette Hollowell, a citizen of the United States, residing at Detroit, in the county of Wayne and State of Michigan, have invented a new, original, and ornamental Design for an Amusement Bar, of which the following is a specification, reference being had to the accompanying drawing, forming part thereof.

Fig. 1 is a side elevation of the amusement bar, showing my new design.

Fig. 2 is a front view thereof.

Fig. 3 is a sectional view taken along line 3—3 of Fig. 2.

Fig. 4 is a sectional view taken along line 4—4 of Fig. 3.

Fig. 5 is a sectional view taken along line 5—5 of Fig. 2, and

Fig. 6 is a sectional view taken along line 6—6 of Fig. 2.

I claim:

The ornamental design for an amusement bar, as shown.

LAFAYETTE HOLLOWELL.
